END MATCHER, WOODWORKING MACHINE

Davis L. Fair, Louisville, Miss.

Application June 25, 1948, Serial No. 35,180

2 Claims. (Cl. 144—91)

1

This invention relates to end-matchers and broadly speaking the object of my invention may be said to be the provision of an improved construction of end-matcher unit with auxiliary and cooperating work handling mechanism which facilitates and expedites the supply of work pieces to the unit, permitting a greatly increased production.

The end-matcher (considered as a type of machine) is well-known, its purpose being to cut a tongue and a groove respectively on the ends of a board to permit such boards to be interlocked end to end with a tongue and groove joint. The boards are usually similarly tongued and grooved along their sides. While the finishing of boards in this manner is by no means limited thereto, it finds a particular application in the manufacture of hard-wood flooring, and because the shortcomings of end-matchers as hitherto known, arising from their slow rate of feed, are very noticeable in the flooring trade, I shall in the following description from time to time refer specifically to the application of my invention to the production of flooring, but without limiting intent.

My invention will be well understood by reference to the following description, taken in connection with the accompanying drawings wherein:

Fig. 1 is a plan view of the grooving unit of an end-matcher and adjacent portions partly broken away;

Fig. 2 is a side elevation of the unit as seen from the plane of the line 2—2 of Fig. 1.

A groove-cutting unit such as illustrated is ordinarily used with a subsequent tongue-cutting unit, to which the work next passes, directly behind it, the two units constituting the mechanism usually termed an end-matcher. For an understanding of the present invention it is unnecessary to illustrate both units. The collocation of two such units is shown and described in the patent to Rose 1,095,233 of May 5, 1914. Although embodying various differences in construction essential to the realization of the present invention, the unit here shown is similar to that in the Rose patent referred to, to which reference may be made for a fuller description of features of construction not illustrated in detail herein. The drawing illustrates a machine direct driven by electric motors as contrasted with a belt driven machine.

In ordinary use the end-matcher has hitherto been placed at the feeding out end of the regular matcher which matched the sides of the

2

board. The operator (reeder) faced the feeding in the side of the end-matcher and the boards were fed endwise, either directly from the side matcher or otherwise, in front of him and parallel to the front of the machine, that is vertically of the sheet viewing Fig. 1, a stop being usually provided to prevent the leading end of the board which was the first to be operated on from moving too far beyond the operator. It was his job to pick up the successive pieces to place them on the feed chain of the end-matcher by a movement transverse to their length, to be carried by the feed chain past the cutting tools. The job was one requiring skill, coordination and rhythm, even at relatively low rates of feed. The work was also dangerous, with the successive pieces of wood hurtling like heavy arrows along a line across which the operator's hands moved. As the speed of the edge-matcher increased in modern practice it delivered work pieces at a rate beyond the powers of the feeder to keep up with it and in many instances two end-matchers were required for each side-matcher. On discharge from the first unit the board was then moved lengthwise to the front of the second unit which shaped the opposite end to be similarly handled and fed.

In the handling of hard-wood flooring conditions were aggravated. The feeder must handle each piece separately, whatever its length. Generally hard-wood pieces were shorter, and being inherently more valuable small pieces were worked. A defect which would be negligible in a piece of soft wood siding would be inadmissible in a flooring strip and would be cut out by the graders, thus making from a single piece two pieces to be handled by the feeder.

Many attempts have been made to provide automatic feeders for end-matchers but on account of the wide range of lengths coming to the machine in miscellaneous order, these attempts have not come to practical fruition.

Referring now to the drawings, I there show an end-matching unit, specifically a grooving unit, which in many respects is like that shown in the Rose patent above referred to, and may be considered for purposes of the present description as embodying the matcher works proper 8, through which the boards are carried by a feed chain 10 having pusher dogs 12. The pieces are laid on the chain, face up, in front of the pusher dogs which carry them under a hold-down 14 and over spring-supported pressure bars (not illustrated in detail) which press them against the lower surface of a top plate 16 (Fig. 2) which de-

termines the vertical position of the piece being operated on. The pusher dogs advance the work piece past a trim saw 18 operating in the vertical plane the outline of which is shown by a broken line in Fig. 2, which saw squares up the end, and a grooving saw 20 which cuts the groove. The piece is then discharged at the further side of the machine. The verbal description embodied in this paragraph would equally apply to the corresponding unit of the Rose patent just referred to.

In contrast with the construction shown in that patent the chain 10 is herein extended outwardly for a considerable distance from the feeding-in end of the machine, that is, toward the left in the figures, to provide at that side as seen therein an extended portion of the horizontal upper run of the chain which is in effect a long table having an unobstructed horizontal top. In the particular machine illustrated, as contrasted with a like machine as hitherto constructed, the extension of the table was in fact three feet, that is, the center of the chain-supporting roller at the left-hand end, viewing the figures, was three feet farther from the location of the hold-down 14 than before. Generally expressed, the horizontal length of the so-called table corresponds at least to the length of several links of the feed chain or several times the spacing of the feeder dogs 12, or several times the average width of the boards which are to be operated on. By several I mean more than one or two, although not many. A number of boards thus may lie engaged with the chain and be moving forward therewith prior to entering under the hold-down 14.

There is thus provided beside the table on that side thereof where the saws 18 and 20 are located and where the legend "Fig. 1" is written on that figure, a station where the feeder (operator) may stand facing transversely to the direction of feed, that is looking downwardly in Fig. 1 or toward the reader in Fig. 2.

Opposite the feeder's station, on the further side of the feed chain from his point of view, a long conveyor 22 is provided herein shown as a belt. This extends to the left in Fig. 1 as far as desired and its upper run parallels the side of the table and moves at the same speed. The width of the belt may be chosen to accommodate in stable position at least the majority of the pieces operated upon. I have herein shown also a conveyor chain 24. Its upper run parallels and moves with the belt 22 and may support the ends of long pieces. The showing of this chain also indicates that the conveyor 22 need not necessarily be a single wide belt as herein illustrated.

The pieces to be operated on are laid transversely on the belt 22 at some point to the left, viewing Fig. 1, usually by the graders, face up and with one end near that side of the belt which is nearer the feed chain 10 and at least roughly parallel to one another and roughly at right angles to the length of the belt. The ends need not be exactly aligned. By way of graphic illustration I have shown in Fig. 1 the end portions of four work pieces *w* irregularly spaced and with their ends disaligned. In general it will be understood that a substantially unbroken succession of pieces will be maintained on the belt.

As the pieces on the belt 22 arrive at the side of the extended portion of the feed chain 10 which has been referred to as a table and at the opposite side of which the feeder takes his stand,

their ends are within the reach of the feeder who may reach across the chain to seize the end of a piece in his hand to draw it endwise toward himself over the table into position in front of one of the pusher dogs 12. This transfer is between two parts moving at the same speed and no substantial transverse movement of the relatively long board is required. The action of the pusher dogs will correct slight misalignments. The weight of the piece is supported and no skill and little manual strength are required.

To facilitate this transfer I prefer to provide along the side of the table where the man stands a fence 26. The feeder may draw the boards toward him until their ends come against the fence, thus positioning the ends relative to the trim saw for economical operation of the latter. The fence relieves him of any need for attending to the exact longitudinal position of the transferred boards and it also protects him from contact therewith, and these two factors permit him to operate quickly. He may work with both hands, seizing a board with each. Since several boards may be positioned on the extended table-like portion of the feed chain 10 at one time the feeder's movements need not necessarily be timed in strict one to one ratio to the supply of boards even when he keeps the chain full, a fact which considerably eases his labor.

Referring to the drawings, and more particularly Fig. 1, it will be seen that I have there illustrated a pusher dog 12 on each link of the chain 10. It has hitherto been customary to provide a pusher dog on alternate links only, even though the length of the links is such relative to the work that a board of the width being worked upon could be accommodated in the space between adjacent pivotal centers of the links. This was because the feeder could not work fast enough to supply a piece of work to each link. In fact he could not consistently keep the chain full with a pusher dog on every alternate link. With the arrangement shown, even a less skilled operator can work so much faster that he can keep the chain at least reasonably full with twice as many dogs as is here illustrated. This illustrates the advantage of the invention, as in such case the feeding rate is substantially doubled. However, even if the pusher dogs are less numerous, as in the machines of the prior art, the method of feeding is of great advantage, permitting faster operation and requiring less skilled labor. Whereas previously a good feeder for an end-matcher was a highly skilled man and relatively hard to find, no particular skill is required with the construction described.

On discharge from the grooving unit shown the pieces pass to a tonguing unit. They are arranged with approximate end alignment of the unfinished ends on a conveyor similar to the conveyor 22 and are transferred to a similarly extended table-like portion of the feed chain on the tonguing unit. While the latter unit utilizes two saws to form the tongue in gross outline the units are alike but one right hand and one left in the relative disposition of their component parts.

I am aware that the invention may be embodied in other specific forms without departing from the spirit or essential attributes thereof, and I therefore desire the present embodiment to be considered in all respects as illustrative and not restrictive, as is in fact clear in several matters from the description itself. Reference is to be had to the appended claims to indicate those

principles of the invention exemplified by the particular embodiment described and which I desire to secure by Letters Patent.

I claim:

1. An end-matching machine of the type wherein a beltlike, endless chain is provided with pusher dogs, which dogs engage the side of a board to be matched adjacent the end thereof, advance the board sideways through suitable supporting means and past the tools which shape the end, the said machine being characterized by the fact that the upper horizontal run of the chain extends forwardly from the feeding-in end for a length several times the spacing of the dogs, such extension providing in effect a long table having an unobstructed horizontal top beside which a man may stand, at the feeding-in end of the machine on the side where the tools are located, and facing transversely to the direction of feed, and further being characterized by the fact that a relatively wider, long, endless conveyor mechanism is supported at the side of said endless chain opposite the operator's station, the conveyor having its upper run moving from a point in advance of the machine parallel to and in the same vertical plane with said endless chain and to a point beyond the operator's station toward the discharge end of the machine, the conveyor being adapted to carry sidewise in the direction of the machine feed successive boards in at least roughly parallel and end-aligned relation to positions within reach of the operator who may thus draw them endwise toward himself over the table into position in front of the pusher dogs.

2. An end-matching machine of the type wherein a relatively wide, endless chain is provided with pusher dogs, which dogs engage the side of a board to be matched adjacent the ends thereof, advance the boards sideways through suitable supporting means and past the tools which shape the ends of said boards, the said machine being

characterized by the fact that the upper horizontal run of the chain extends forwardly from the feeding-in end for a length several times the spacing of the dogs, such extension providing in effect an oblong, horizontal supporting surface beside which a man may stand, at the feeding-in end of the machine on the side where the tools are located, and facing transversely to the direction of feed, and further being characterized by the fact that a relatively wider, long, endless conveyor mechanism is supported at the side of said endless chain opposite the operator's station, the conveyor having its upper run moving from a point in advance of the machine parallel to and in the same vertical plane with said endless chain and to a point beyond the operator's station toward the discharge end of the machine, the conveyor being adapted to carry sidewise in the direction of the machine feed successive boards in at least roughly parallel and end-aligned relation to positions within reach of the operator who may thus draw them endwise toward himself transversely of said conveyor mechanism into position in front of the pusher dogs of said endless chain, the table having a fence along the operator's side thereof against which the ends of the boards may be drawn.
